1 Claim. (Cl. 122—225)

While the flue gases of a heater, coming from the fire-zone, sweep along the heating faces, they successively deliver heat thereto and are cooled in turn. Their volume is decreased thereby so that their velocity also drops if the flow cross-section remains unchanged. This again causes a drop of the heat-transfer coefficient, the so-called K value, so that the decrease of the specific load of the heating face (B.t.u./sq.ft./h.) is influenced in a double sense, i.e. not only by the decrease in the temperature difference.

The subject matter of my present invention are heaters in which the flow cross-section of the combustion gases is gradually restricted while they are progressively cooled, as far as possible so that their decrease in volume is over-compensated, i.e. that their velocity is increased thereby. The so-called K value (B.t.u./sq.ft./h./° F.) also is increased, however, so that the heat transfer, i.e. the specific load, may be held substantially constant.

One form of the present invention is shown in the form of an oil-fired sectional boiler adapted for conversion to coal-firing. In the drawing—

FIGS. 1 and 3 show a more or less schematical vertical section through the boiler, FIG. 1 being the version adapted for coal-firing, and FIG. 3 being the version adapted for oil-firing, and

FIGS. 2A and 2B showing horizontal sections E—E and E'—E' respectively in FIG. 1.

This continual decrease of the combustion-gas flow zone G by the lateral slant of the fuel or fire-chamber, brought about by the ribs Ri which taper-off upwardly, is so chosen in accordance with the invention that not only will be balanced the decrease in volume of the gases by cooling, but the gases will be accelerated yet.

Since in this arrangement a gas-generator effect and dry distillation may arise in fire-zone F and in the solid fuel, firing is carried out to advantage with excess air, i.e. so that the oxygen residual of the combustion gases above the fuel and in the upper portion of chamber G suffices for possible afterburning. As the combustion air enters through ashpit A, it partly will flow through grate Ro, as indicated by the arrows, partly however rise directly in space G, supply with oxygen the fire-zone laterally adjacent to the ribs Ri and arrive as secondary air also in the space above the fuel B.

The heater shown in FIG. 1 is eminently suited for

2

oil-firing, but may readily be converted to cool firing. F1 denotes the oil-burner flame, Sp is the lateral lining of the fire-chamber with fire-clay plates, and Sg denotes the cover of the fire-chamber, comprising fire-clay vault bricks. In this arrangement, the fire-clay bricks or plates Sp are set up, i.e. leaned against the ribs, so as to seal as tightly as possible the gas-flow space G from the fire-chamber. The combustion gases of the flame F1 now are forced, as indicated by arrows, to first flow downwardly, then pass through the grate and flow, in accordance with the invention, through the tapering space G. Owing to this passage of the combustion gases through the grate, the grate advantageously is water-cooled, and thereby will also represent a heating surface.

When it is desired to convert the boiler shown to coal firing, the refractory lining and vault bricks Sp and Sg are removed. In such case, a portion of the combustion air rises from ashpit A through the water-cooled grate Ro to maintain combustion in the coal heap while another portion of the air rises through the flues G to pass partly into the coal heap laterally and partly as secondary air into the fire space above the coal heap.

What I claim as new and desire to secure by Letters Patent, is:

25 In a single-pass hot-water heating boiler comprising water-containing boiler sections, a water-bearing grate integral with said sections, said sections forming between them flues of upwardly constantly decreasing cross-section laterally open to the inside, a firebox having upwardly diverging sides defined by said sections, an ashpit communicating with said flues, and top outlets for said flues, the improvement comprising removably assembled fire-clay bricks lining the firebox sides and being set on edge loosely on top of each other, and a plurality of loosely 30 and removably assembled arched fireclay bricks to form 35 a vault bearing on the top edges of the brick lining.
